UNITED STATES PATENT OFFICE.

JOHN RIDDELL, OF SCHENECTADY, NEW YORK, ASSIGNOR TO GENERAL ELECTRIC COMPANY, A CORPORATION OF NEW YORK.

BORING AND TURNING MILL.

No. 834,218.

Specification of Letters Patent.

Patented Oct. 23, 1906.

Original application filed June 27, 1903, Serial No. 163,319. Divided and this application filed May 19, 1905, Serial No. 261,138.

To all whom it may concern:

Be it known that I, JOHN RIDDELL, a citizen of the United States, residing at Schenectady, in the county of Schenectady and State 5 of New York, have invented certain new and useful Improvements in Boring and Turning Mills, (division of my prior application, Serial No. 163,319, filed June 27, 1903,) of which the following is a specification.

10 The present invention relates to machine-tools, and more particularly to boring and turning mills, and has for its object to provide a boring-bar which may be raised or lowered into adjusted position by hydraulic means, and, further, to provide a tool-head which may be readily adjusted rotarily upon the bar and also caused to move longitudinally thereof by the same hydraulic means used in adjusting the bar.

20 In the accompanying drawings, forming a part of this specification, Figure 1 is a vertical section of the boring-bar and tool-head. Fig. 2 is a cross-section of the saddle and cross-beam of a boring-mill with the boring-bar connected thereto. Fig. 3 is a horizontal section of the bar and tool-head, and Fig. 4 is a front elevation of the upper end of the boring-bar and its supporting-head.

25 The saddle 1 is provided in its back side with bearing-surfaces 2 3 4, which engage ways 5 6 7 on the cross-beam 8 of the mill, so that the former may move longitudinally of the latter, and in the front side of the saddle is formed an undercut circular groove 9 on the back side of the swiveled bar-head 11, which is adapted to be clamped in adjusted position by bolts 12, having nuts located in the undercut groove 9. The bar-head 11 has on its front side two clamping-boxes 13 30 14 for the reception of the boring-bar 15 with removable covers 16 17, adapted to be clamped upon the bar by bolts 18 to hold the bar in adjusted position.

35 The boring-bar 15 is in the form of a hollow cylinder with keyways 19 on opposite sides and a stuffing-box 20 at its upper end. The lower end of the bar is closed, and in order that it may be rigidly clamped to the floor or other stationary part a flanged collar 21 is removably bolted to its lower end. A piston 22 is arranged within the bar 15 and connected by an axially-apertured rod 23, which extends through the stuffing-box 20, to

a cross-head 24. The upper end of the hollow rod 23 is adapted to be connected with 55 means for supplying pressure liquid therethrough, as will be explained later.

The opposite ends of the cross-head 24 are apertured for the reception of the upper ends of rectangular rods 25, which are loosely arranged in the keyways 19 and connect at their lower ends with the quill 26, upon which the tool-head 27 is swiveled. The quill 26 has feathers 28 engaging the keyways 19 in the boring-bar to prevent rotary movement 65 thereon, and in its outer surface it is turned up to provide a bearing-surface for the sleeve 29, and about half-way between its ends is secured a worm-wheel 30, with which engages a worm 31, carried on a shaft 32, journaled in 70 an extension from the sleeve 29, so that by rotating the worm 31 the sleeve is caused to rotate relatively to the boring-bar. One side of the sleeve 29 is projected out into a plane surface and provided with a circular under-cut groove 33 for the reception of the tool-plate 34, which is clamped thereto in adjusted 75 position by bolts 35.

The upper end of the quill 26 is internally recessed for the reception of the lower ends of 80 the rods 25, which are secured removably thereto by set-screws 36. One of the rods 25 is provided with rack-teeth 37, which mesh with a small gear 38, carried by a stub-shaft on the boring-bar head 11 and rigidly connected to a larger gear 39, which meshes with a pinion 40, fixed to the shaft 41 of a hand-wheel 42, carried by the head 11 and provided with the usual clamping member 43. According to this arrangement the rods 25 85 and the piston 22 carried thereby may readily be raised by rotation of the hand-wheel 42, and after clamping the latter against retrograde movement pressure fluid may be turned into the upper portion of the hollow 90 boring-bar and the latter lifted thereby to the desired height, where it is adapted to be supported by screwing up on the clamping-bolts 12, and after releasing the hand-wheel 42 the tool-head may be fed up and down the boring-bar under control of the pressure fluid. 95

I do not desire to restrict myself to the particular form or arrangement of parts herein described and shown, since it is apparent that they may be changed and modified without 100 departing from my invention. 105

What I claim as new, and desire to secure by Letters Patent of the United States, is—

1. In a boring and turning mill, the combination of a cylindrical boring-bar, a sleeve feathered thereto for longitudinal movement, an adjustable tool-supporting shell journaled upon said sleeve, and means to move said shell about said sleeve and hold it in adjusted position.
2. In a boring and turning mill, the combination of a cylindrical boring-bar, a sleeve feathered thereto for longitudinal movement and provided with a fixed worm-wheel, and an adjustable tool-supporting shell journaled upon said sleeve and provided with a worm adapted to engage said worm-wheel.
3. In a boring and turning mill, the combination of a hollow boring-bar, a piston located therein, rods connected to said piston

and extending parallel to said boring-bar, 20 and a tool-support mounted to travel upon said bar and connected to said rods.

4. In a boring and turning mill, the combination of a hollow boring-bar, a piston located therein, a head in which said bar is longitudinally adjustable, a rod provided with a 25 rack and connected to said piston, a tool-support mounted to travel upon said bar and connected to said rod, and a hand-operated wheel journaled in said head and geared to 30 said rack.

In witness whereof I have hereunto set my hand this 17th day of May, 1905.

JOHN RIDDELL.
